UNITED STATES PATENT OFFICE

CHARLES H. JOHNSON, OF SACRAMENTO, CALIFORNIA

THIMBLE STRUCTURE

Application filed August 1, 1928. Serial No. 296,802.

This invention relates to a thimble structure, whereby a chimney and stovepipe are connected, and especially to a sub-thimble, whereby breaking of the chimney thimble and cracking of the interior plastered wall surface of a building is prevented and settling of the chimney or building takes place.

The object of the present invention is to generally improve and simplify the construction and operation of thimbles of the character described, and especially to provide a sub-thimble which is adapted to be interposed between the chimney thimble and a wall structure in such a manner as to relieve the wall structure and the chimney thimble of all strains when settling of the building or chimney takes place, thereby preventing breaking of the chimney thimble and cracking of the interior plastered surface of the wall.

20 The thimble structure is shown by way of illustration in the accompanying drawings, in which—

Fig. 1 is a sectional view of a chimney and a wall structure, showing the ordinary method of supporting the chimney thimble.

Fig. 2 is a similar section, showing the thimble structure forming the subject-matter of the present application.

Fig. 3 is an enlarged cross section, taken on the line 3—3 of Fig. 2.

Referring to the drawings in detail, and particularly Fig. 1, it might be stated that when an ordinary wooden building is constructed the studding is erected, as indicated at 2. The lath 3 is nailed to the inner surface of the studding and the plaster is then applied, as indicated at 4. The chimney, usually built of brick, is indicated at 5. It is built exteriorly of the building and in contact either with the studding 2 or with sheeting applied thereto.

In the kitchen where stoves are used a connection must be formed between the stovepipe and the chimney and a terra cotta pipe is usually employed for this purpose. The terra cotta pipe is usually embedded in the brickwork of the chimney and the building trade refers to it as a thimble. The opposite end of the terra cotta pipe or thimble is supported by the lath and the plaster. The

thimble is indicated at 6. The end which is secured in the chimney is shown at 7, and the opposite end, supported by the lath and plaster, is indicated at 8.

After the building has been completed either the building or the chimney is subjected to a certain amount of settling. In some instances the chimney settles as much as one-quarter to one-half inch with relation to the building and something must give. That is, either the thimble, indicated at 6, cracks or breaks or the lath and plaster give way, causing a cracked surface to appear on the inside of the building. The result is of course not only undesirable, as it mars the wall surface, but the main objection is the fire danger. That is, breaking of the thimble will permit sparks and soot to drop between the chimney and the frame of the building and a fire is liable to start at any time.

The purpose of the present invention is to provide a thimble structure which will entirely obviate this fire danger and, furthermore, save the interior plastered surface from cracking and mutilation. The building is erected in the usual manner as are also the chimney and thimble. That is, the inner end of the thimble is secured in the brickwork, as indicated at 9. After the thimble has been placed in position and secured a sub-thimble is applied, as indicated at 10. The thimble is made of sheet iron or like material and is provided with annular flanges 11 and 12 at opposite ends. A plurality of resilient fingers 14 is secured to the inner face of the thimble ring, and these fingers serve the function of normally maintaining the thimbles concentric with relation to each other.

In actual construction, the sub-thimble is slipped over the inner end of the chimney thimble 6 and it is held concentric with relation to the chimney thimble by means of the resilient fingers 14. The lather then comes along and brings the lath up to the sub-thimble, as shown at 15 (see Fig. 3) and the plaster is then finally applied, as indicated at 16, and when the plaster finally sets the sub-thimble becomes rigidly secured in the wall structure, while the chimney thimble, which projects therethrough, is free to move in any

direction as settling takes place without imposing any strain either on the plastered surface or either of the thimbles. For instance, if the chimney settles after the building is completed, the fingers 14 will merely yield and the chimney thimble will assume an eccentric position with relation to the sub-thimble. No strain, however, is transmitted either to the chimney thimble or the sub-thimble and cracking of either plaster or the chimney thimble is prevented.

The sub-thimble is considerably larger in diameter than the chimney thimble so as to provide the annular space 18; this space being provided for the fingers 14 and to prevent movement of the thimbles with relation to each other without contacting. This annular space is, in the present instance, closed by a sleeve 19 which is slipped over the inner end of the thimble 6. The sleeve is provided with an annular flange 20, larger in diameter than the sub-thimble 10, and the annular space 18 will thus be covered.

The stove chimney, indicated at 21, will be connected in the usual manner by inserting it in the inner end of the thimble 6, as shown in Fig. 2, and an ornametal pipe collar may be applied, as indicated by dotted lines at 22.

While certain features of the present invention have been more or less specifically described and illustrated, I wish it understood that various changes may be resorted to within the scope of the appended claim; and similarly that the materials and finish of the several parts employed may be such as the experience of the manufacturer may dictate or varying conditions may demand.

Having thus described my invention what I claim and desire to secure by Letters Patent is—

In a structure of the character described a sub-thimble, comprising an elongated cylindrical shaped shell, an annular outwardly extending flange on each end thereof, a plurality of resilient spring fingers secured on the interior surface of the shell, a second thimble of smaller diameter adapted to assume a concentric position within the sub-thimble and a flange formed on the outer end of the second thimble and having a diameter substantially equal to the flanges on the ends of the sub-thimble.

CHARLES H. JOHNSON.
